WINDOW CLEANING DEVICE

David M. Gallagher, Milford, Conn.

Application June 9, 1949, Serial No. 98,115

6 Claims. (Cl. 15—250)

1

The present invention relates to window cleaning devices, and has special reference to a device for use in cleaning windows of the sliding upper and lower sash type.

One of the objects of the invention is to provide a device of this character which is of simple and inexpensive construction, and convenient in use.

Another of the objects of the invention is to provide a window cleaning device having a cleaning pad which is adapted to be easily inserted between the upper portion of the lower sash and the lower portion of the upper sash and against the pane of the lower sash, and held in position by being clamped to the lower rail of the upper sash, whereby cleaning of the outer side of the pane of the lower sash may be easily accomplished by raising and lowering the lower sash.

The several features of the invention, whereby these and other objects may be attained, will be readily understood from the following description and accompanying drawings, in which:

Figure 1 is a side view of my improved device shown applied to a window of the sliding upper and lower sash type, portions of the upper and lower sashes being shown in section;

Fig. 2 is a rear view of the device on an enlarged scale;

Fig. 3 is a sectional elevation taken on the line 3—3 of Fig. 2;

Fig. 4 is a detail sectional view taken on the line 4—4 of Fig. 2; and

Fig. 5 is a horizontal sectional view, taken on the line 5—5 of Fig. 2.

The device as illustrated in the drawings, comprises a cleaning pad holder 2 which as shown is in the form of a rectangular plate. A cleaning pad 4 which may be made of any suitable material, such as cloth, sponge, or brush, may be detachably secured to the front side of the holder in any suitable manner such as by folding the upper and lower edges of the pad over the edges of the holder, and securing them as by eyelets 6 on the folded edges that are held by clips 8 on the holder.

On the rear side of the holder is secured a stationary clamping member 10 which has a horizontal projecting flange 12, the portion of the member 10 beneath said flange being inclined downwardly and inwardly. The device is further provided with movable clamping members 14 which, as shown, are formed on the lower ends of rods 16, said members being bent at right angles to the rods. The rods 16 are mounted to slide vertically through apertures in guide plates

18 secured by screws 20 to the underside of the clamping member 10. Each of the rods 16 has a twisted portion 22, and the aperture in associated guide plate 18 through which the rod extends is suitably shaped so that during the downward movement of the rods the rods are turned in a counter-clockwise direction (viewing Fig. 2) so as to turn the clamping members 14 toward the rear side of the pad holder as shown by dotted lines. During the upward movement of the rods 16, they are turned in the opposite direction to position their clamping member 14 substantially at right angles to the back of the holder with their ends directly beneath the clamping

15 flange 12. The upper ends of the clamping rods 16 are mounted for turning movement in apertures in a cross-head or bar 24 and are caused to move vertically with the cross-bar by means of collars 26 secured to the rods adjacent the upper and lower sides of the bar. The bar 24 is guided during its vertical movements by means of rods or pins 28 having their upper ends secured thereto and their lower ends extending through apertures in the 20 guide plates 18. The cross-head 24 is pressed upwardly by means of coiled springs 30 interposed 25 between the top side of the clamping member 10 and the cross-head.

The ends of the cross-head 24 are secured to 30 the ends of a U-shaped frame member 332. To the center of the upper side of the clamping member 10 there is secured, by means of a screw 34, the lower end of an upright frame member 36. The upper portion of the frame member extends 35 through a guideway formed between the side of the U-shaped frame member 32 and a strap 38 secured to a boss on the latter by means of rivets 40. One side of this upright frame member 36 is provided with serrations 42, and the other side is adapted to be engaged by the eccentric end of 40 a clamping lever 44, whereby upon swinging the lever 44 downwardly as indicated by the arrow shown in Fig. 2, the upright member 36 is clamped to the U-shaped member 32 so as to hold the upright member from upward movement against the tension of the springs 30. A lever 46 is pivotally mounted at 48 on the upright member 36, and has its lower end engaging the top side of the cross-head 24.

With this construction, to apply the device to the window, as shown in Fig. 1, the clamping lever 44 is turned to its released position as shown in Fig. 2, and then the lever 46 is turned in a counterclockwise direction so as to cause its lower end by engagement with the cross-bar 24 to force

the bar downwardly against the tension of the springs 30 until the lever has been turned into vertical position, whereupon the bar is held thereby by the lever. Also, the bar 24 may be further locked in depressed position by means of the eccentric lever 44. During such downward movement of the bar 24, the clamping members 14 are moved downwardly with the bar and are retracted as above described and as shown by dotted lines in Fig. 2.

With the device thus set, it is ready to be applied to the window illustrated in Fig. 1. This window has upper and lower sashes, the upper sash comprising a lower rail 50 and a window pane 52, and the lower sash having an upper rail 54 and a window pane 56. To apply the device, the lower sash of the window may be raised to substantially the position shown in Fig. 1, and the device inserted between the upper portion of the lower sash and the lower portion 20 of the upper sash, so as to position the cleaning pad 4 against the pane of the lower sash with the clamping flange 12 engaging the top side of the lower rail of the upper sash, the portion of the clamping member 10 below the flange 12 substantially fitting the inner side of said lower rail. As the clamping members 14 are in their said retracted position during such insertion of the device, they are free to clear the lower rail. When the device is thus positioned, the cam lever 44 is turned to release the U-shaped frame member 32 and the lever 46 is turned in a clockwise direction so as to release its lower end from holding engagement with the cross-head bar 24, whereupon the springs 30 forcefully move the bar 24 upwardly, thus causing the clamping members 14 to be raised and turned so as to engage the underside of the lower rail of the upper sash, and thus cooperate with the clamping flange 12 to firmly clamp the device to the lower rail 50. When the device is thus clamped to the rail 50 it may be positively held in position by means of the eccentric lever 44.

With the device thus applied, the cleaning of the outer side of the pane of the lower sash may be easily accomplished by raising and lowering, one or more times, the lower sash so as to cause the window pane to rub against the cleaning pad 4. When a portion of the pane has been thus cleaned the width of the pad, the device may be easily shifted laterally to clean the remaining portions of the outer side of the lower pane.

At the completion of the cleaning, the device may be easily removed from the window upon releasing the cam lever 44, and again turning the lever 46 in a counter-clockwise direction so as to depress the cross-head bar 24, and thus move the clamping members 14 into their retracted positions, thus releasing the device from the upper sash and permitting said members to clear the lower rail of the sash as the device is being lifted from between the window sashes.

It will be apparent that my improved device may be easily and quickly applied to clean the outer side of the pane of the lower sash, which is the most difficult part of the window to reach from the inside of a building. When the window is open, the outside of the upper pane can be easily cleaned with ordinary brushes or cleaners, but the outside of the lower pane is out of reach.

The device is substantially foolproof, and the confined space within which it is located prevents meddling with it when in position, and it cannot be dropped through or fall out of the window while in use. Any desired pressure of the clean-

ing pad on the window may be obtained by adjustment of the clamp on the window sash.

As will be evident to those skilled in the art, my invention permits various modifications without departing from the spirit thereof or the scope of the appended claims.

What I claim is:

1. A cleaning device for a window of the sliding upper and lower sash type comprising a holder for a cleaning pad, the holder and pad being adapted to be inserted through the space between the upper portion of the lower sash and the lower rail of the upper sash with the pad engaging the outer side of the pane of the lower sash when the lower sash is partially raised, a clamping member mounted on the back of said pad holder for engagement with the top side of the lower rail of the upper sash when the holder and pad are thus positioned, and a cooperating clamping member adapted to be turned to a position to clear the lower rail of the upper sash when the holder and pad are being moved into said position, and then to be turned to project beneath the lower rail of the upper sash and to be raised to engage the underside of said lower rail to cooperate with the first-mentioned clamping member to hold said holder and pad in said position, a support on the lower portion of which said holder is mounted, and means comprising devices mounted on said support and manually operable from points spaced a distance above the holder for thus operating said second-mentioned clamping member.

2. A cleaning device for a window of the sliding upper and lower sash type, comprising a holder for a cleaning pad, the holder and pad being adapted to be inserted through the space between the upper portion of the lower sash and the lower rail of the upper sash with the pad engaging the outer side of the pane of the lower sash when the lower sash is partially raised, clamping members mounted on the back of said holder adapted to be relatively moved to engage the upper and lower sides of the lower rail of the upper sash to hold said holder and pad in said position, a support on the lower portion of which said holder is mounted, and means comprising devices mounted on said support and manually operable from points spaced a distance above the holder for thus relatively moving said clamping members.

3. A cleaning device for a window of the sliding upper and lower sash type comprising a holder for a cleaning pad, the holder and pad being adapted to be inserted through the space between the upper portion of the lower sash and the lower rail of the upper sash with the pad engaging the outer side of the pane of the lower sash when the lower sash is partially raised, and a cooperating clamping member adapted to be retracted to clear the lower rail of the upper sash when the holder and pad are being moved into said position and then to be projected beneath the first-mentioned clamping member and moved upwardly to engage the underside of the lower rail, a support on the lower portion of which said holder is mounted, and means comprising devices mounted on said support and manually operable from points spaced a distance above the holder for thus operating said second-mentioned clamping member.

4. A cleaning device for a window of the sliding upper and lower sash type comprising a holder for a cleaning pad, the holder and pad being adapted to be inserted through the space between

the upper portion of the lower sash and the lower rail of the upper sash with the pad engaging the outer side of the pane of the lower sash when the lower sash is partially raised, upper and lower clamping members for clamping engagement with the top and bottom sides of the lower rail of the upper sash when the holder and pad are thus positioned, the lower clamping member comprising a rod vertically arranged having a laterally projecting lower end for clamping engagement with the bottom side of said lower rail, a guide in which said rod is mounted for vertical movement, said guide and rod having co-engaging parts whereby during downward and upward movements the rod is turned to retract and project said lateral projecting end thereof respectively, a cross-bar connected with the upper end of said rod for thus moving said rod vertically, a spring pressing the cross-bar upwardly, and means comprising a lever operable from a point a distance above the pad holder for engaging the cross-bar to move it downwardly against the tension of its spring.

5. A cleaning device for a window of the sliding upper and lower sash type comprising a holder for a cleaning pad, the holder and pad being adapted to be inserted through the space between the upper portion of the lower sash and the lower rail of the upper sash with the pad engaging the outer side of the pane of the lower sash when the lower sash is partially raised, upper and lower clamping members mounted on the back of said pad holder for respectively engaging the top and bottom sides of the lower rail of the upper sash when the holder and pad are thus positioned, and devices for moving the lower clamping member downwardly and for retracting it so as to clear the lower rail of the upper sash when the holder and pad are being moved into said position, and for projecting the lower clamping member after it passes beneath said rail and raising it into clamping engagement with the underside of said rail to cooperate with the first-mentioned clamping member to hold said holder and pad in said position, including releasable means operable a distance above the pad holder for positively holding said clamping members in clamping engagement with said lower rail.

6. A cleaning device for a window of the sliding upper and lower sash type comprising a holder for a cleaning pad, a clamping member mounted on the back of the holder having a

5 rearwardly projecting flange for engagement with the top side of the lower rail of the upper sash with the cleaning pad positioned against the outer side of the pane of the lower sash, a cross-bar arranged above said clamping member, means for guiding said cross-bar for vertical movement, means for yieldingly pressing the cross-bar upwardly, vertically extending rods having their upper ends rotatably secured to the cross-bar, guides mounted on the back of the holder having guiding apertures through which the lower portions of said rods extend, said rods having laterally projecting clamping members formed on their lower ends, said rods and the walls of said guiding apertures being shaped so that upon said cross-bar being moved downwardly the rods are turned in a direction to retract said clamping members thereon from beneath said first-mentioned clamping member, and upon being moved upwardly the rods are turned to project the clamping members thereon into position beneath said first-mentioned clamping member and to cause the clamping members on the rods to engage the underside of the lower rail of the upper sash to cooperate with the first-mentioned clamping member to clamp said lower rail between them, a vertically extending frame member having its lower end secured to the first-mentioned clamping member, a U-shaped frame having its ends secured to said cross-bar, the upper portion of said U-shaped frame having a guiding opening through which the upper end portion of said frame member extends, means for releasably clamping said frame member and said U-shaped frame together, and means for moving said cross-bar downwardly comprising a lever pivotally mounted on said frame member with its lower end engaging the top side of said cross-bar.
